UNITED STATES PATENT OFFICE.

ALFRED H. RENSHAW, OF TROY, NEW YORK, ASSIGNOR TO STANDARD SIGNAL COMPANY, OF TROY, NEW YORK.

GUIDE FOR SWITCH AND SIGNAL RODS.

SPECIFICATION forming part of Letters Patent No. 690,183, dated December 31, 1901.

Application filed September 6, 1901. Serial No. 74,551. (No model.)

To all whom it may concern:

Be it known that I, ALFRED H. RENSHAW, a citizen of the United States, residing at Troy, county of Rensselaer, and State of New York, have invented certain new and useful Improvements in Guides for Switch and Signal Rods, of which the following is a specification.

The invention relates to such improvements; and it consists of the novel construction and combination of parts hereinafter described and subsequently claimed.

Reference may be had to the accompanying drawings, and to the reference characters marked thereon, which form a part of this specification.

Similar characters refer to similar parts in the several figures.

Figure 1 of the drawings is a view in elevation, showing the invention applied to a series of guides for switch and signal rods. Fig. 2 is a view of the same, partly in top plan and partly in horizontal section, on the broken line 2 2 in Fig. 1. Fig. 3 is a top plan view of one of the retaining roller-supporting shafts detached. Fig. 4 is a view in side elevation of one of the standards.

This invention relates to antifriction supporting and guiding mechanism for rods used for the positive operation of switches and signals in connection with railway systems.

The objects of the invention are to simplify the construction, reduce the number of parts, and provide for the accurate spacing of the supporting-standards for the guide mechanism. The standards are preferably interchangeable and adapted for use in series.

Referring to the drawings, the standards are shown each comprising an upright 1, having on its lower end feet 2, adapted to be bolted to a suitable support and of a width adapted by engagement of those of one standard with those of the adjacent standards to secure proper spacing of the lower ends of the standards when arranged in a group or series in use. Each upright is provided with a horizontal slot 3, bordered by the flange 4, which slot is adapted to receive and form bearings on opposite sides of the standard for the neighboring trunnions 5 of neighboring supporting-rollers 6, peripherally grooved to re-

ceive and support the signal or switch operating rods. A portion of the flange 4 on each side of the upright is removed, as shown at 7, forming an opening leading from the upper side of the bearing-slot, through which the trunnion 5 is free to pass in removing the roller 6 from or placing it in its bearings. The supporting-roller can thus be removed and replaced without separating the standards.

The upper end of each upright is provided on opposite sides with similar recesses 8, separated by the diaphragm or web 9, each of which recesses has a top opening of approximately the same area as the recess, and a contracted slotted lateral aperture 10, continuous with the top opening. The contracted slotted lateral aperture is formed by introverted lugs or flanges 11, forming part of the upright casting.

The retaining-roller 12 is mounted above the supporting-roller 6 between the upper ends of the standards upon the shaft 13, and the ends of said shaft are inserted in the respective recesses 8. The shaft 13 is preferably of a diameter greater than the width of the slots 10 and is provided near its ends with contracted portions 14, adapted to enter and fit said slots when the ends of the shaft, which remain of the normal diameter, are inserted in the respective recesses 8. The portions of the shaft adjacent to the contracted portions 14 form offsets or abutments 15, which engage and closely fit the flanges 11, adjacent to the slots 10, and thus rigidly connect together the edges of neighboring standards, maintaining the same properly spaced.

It will be seen that the retaining-roller-supporting shafts can be easily and quickly inserted and removed through the upper open ends of the recesses 8.

As a preferred means for securing the shafts against upward displacement in their bearings a retaining key or pin 16 is inserted through an aperture 17 in the web 9 in position to overhang neighboring ends of neighboring shafts 13, a single pin or retainer thus serving to lock both shafts in their bearings.

The improved standards above described can be easily cast ready for use without drilling or machine-work, and a simple swaging operation is sufficient to form the contracted

portions of the shaft, which itself forms the sole spacing mechanism for the upper ends of the standards, and while the construction is inexpensive it is highly efficient to maintain 5 the standards properly spaced. The standards, being interchangeable and reversible, can be thus connected in series by a succession of comparatively short shafts 13, permitting the removal of any one shaft, with its roller 12, 10 without interference with the other members of the series.

What I claim as new, and desire to secure by Letters Patent, is—

1. The combination with a pair of standards, of a supporting-roller journaled in said standards; a retaining-roller; and a shaft for the retaining-roller having end bearings in said standards; and interengaging offsets on the ends of said shaft integral therewith and 20 walls of said bearings integral therewith respectively, substantially as described.

2. The combination with a standard having in its upper end a recess with a contracted lateral opening; of a roller-supporting shaft 25 inserted in said opening and provided with an end offset located in said recess, substantially as described.

3. The combination with a standard provided in its upper end with a recess having a

top opening of approximately the same area 30 as the recess and a contracted slotted lateral aperture continuous with the top opening; of a roller-supporting shaft having a contracted portion seated in said slotted lateral aperture, and an offsetting end portion located in 35 said recess; and retaining mechanism overhanging said shaft, substantially as described.

4. In combination, a plurality of standards adapted for use in series, each comprising an upright having in its upper end bearing-recesses opening upwardly and in opposite directions laterally, and separated from each other by an apertured web; of supporting-rollers journaled in said standards; retaining-rollers; and shafts supporting said retaining-rollers and having the neighboring ends of two shafts seated in the oppositely-opening recesses in one of said uprights; and retaining mechanism secured in the aperture in said web, and overhanging the ends of both 50 said shafts, substantially as described.

In testimony whereof I have hereunto set my hand this 31st day of August, 1901.

A. H. RENSHAW.
